UNITED STATES PATENT OFFICE

2,503,722

FOG NOZZLE

Thomas J. Gothard, Los Angeles, Calif., assignor
to Richard Wunn, Long Beach, Calif.

Application November 16, 1943, Serial No. 510,453

7 Claims. (Cl. 299—62)

1

This invention relates to devices used for generating finely divided vapor which has the appearance of a fog.

Fog nozzles, generally in use, are commonly designed to discharge in one certain direction, upwardly, forwardly, sidewise, or just plainly causing a descending of the discharge as soon as escaping from the nozzle; perhaps, mostly due to being too heavy, or not sufficiently vaporized into a really finely divided mist.

Moreover, conditions may require a smaller or larger volume of discharge on different occasions, for different purposes from the same source, with an assurance of an evenly divided spray in any particular actually delivered volume. Other requirements may call for a maximum discharge at one time and, then again, a possibly complete shut-off at another time. Any of such conditions or requirements are difficult of fulfillment by unskilled labor with devices commonly in use.

It is a very well established fact that vaporizing does not really depend so much on fineness of orifices or passages; but rather much more on a thorough diffusing and dividing of particles of any matter to be vaporized; and there are well-known means for diffusing or dividing particles for any such purposes.

The present device is, therefore, principally designed for simplicity in manufacturing as well as in operation and in application for different purposes.

The present invention is intended to allow adjustments for different purposes with one and the same device, to assure predetermined different results even if installed by unskilled labor in different places.

To provide for all such possibilities, the present device is designed with various arrangements, adjustments, as well as constructive differences. Distinctly different constructions may eventually be selected in different localities, for really distinct purposes.

One of the objects of this invention is, nevertheless, in addition to the desirability for simplicity, to make adjustments possible for the finest and most evenly divided discharge wherever required or desired, without sacrificing the principles of embodied simplicity.

A distinct object of this invention is to provide a device that may readily be adjusted between limits of a full capacity discharge and a complete shut-off.

Another object is to provide means by which the discharge can be directed with a distinctly

2

greater force upwardly, downwardly, or in a more or less sidewise direction.

Another object is to provide means by which one or the other of oppositely arranged discharges may be operated separately without the other.

Another object is to provide means by which oppositely arranged discharges may be actuated in a circular path jointly following the same circulating direction.

Another object is to provide means by which oppositely arranged discharges may be actuated in a circular path separately following opposite circulating directions.

Another object is to provide a device designed as a whole for utmost simplicity.

Another object is to provide oppositely arranged rings that may easily be produced by die-casting, by having the exacting work for nozzle-formations in the co-acting faces of the rings; each of the rings having nozzle-portions to, either, cooperatively join the other in a complete nozzle for operation in the same direction, or such nozzle-portions to point in opposite directions for operations in opposite directions.

Another object is to provide an equalizing bowl, assuring an elimination or counteraction of air pockets in the supply or pressure under which the device is operating, and to facilitate the insertion of fine filtration by enclosed filter material.

Other objects may be visualized from the following description and claims, as well as from the accompanying drawings, in which—

Fig. 1 is a vertical midsectional view of the fog nozzle in the simplest form, L and R referring to the more accurate lines of cutting indicated in Fig. 6.

Fig. 2 is a fragmentary horizontal view of the combined two jet-rings in which one jet-half points in one direction and the other jet-half points in the opposite direction, both jet-halves being in the same direction when turned face up as in Fig. 10.

Fig. 3 is a cross section on line 3—3 of Fig. 2.

Fig. 4 is a cross section on line 4—4 of Fig. 2.

Fig. 5 is a cross section on line 5—5 of Fig. 2.

Fig. 6 is a fragmentary horizontal view of the combined two jet-rings in which both jet-halves point in the same direction; the jet-halves being in opposite directions when turned face up as in the combined two illustrations of Figs. 10 and 11.

Fig. 7 is a cross section on line 7—7 of Fig. 6.

Fig. 8 is a cross section on line 8—8 of Fig. 6.

Fig. 9 is a fragmentary illustration of a slightly

modified form of nozzle construction, when compared with Fig. 1, with adjustments for the discharge, and with the separating disc extending through the outside of the rotor.

Fig. 10 is a fragmentary horizontal section on line 10—10 of Fig. 9.

Fig. 11 is a detail illustration of a nozzle-recess pointing in the opposite direction compared with the illustration in Fig. 10.

Fig. 12 is a fragmentary detail illustration of oppositely arranged rotor-halves, the two halves having a pin-engagement with centrally disposed disc by which both rotor-halves are controlled for joint movement in the same rotating direction.

Fig. 13 is a cross section through the separating disc of a slightly modified form by which the stream may be diverted outwardly from the center of oppositely arranged rotor-halves.

Fig. 14 is a fragmentary vertical section through rotor and impingement-rings, having inturned tips on both impingement-rings over the rotor close to the center of the rotor.

As illustrated in the simplest form of Fig. 1, for the supply coming through the inlet connection 7 of the main housing 8, an escape is provided through the several openings 9. About this portion of the housing, and in cooperative relation to these openings, are the jet-rings 10 and the rotor 11.

The cap 12 serves to close the upper end of the housing, and, with its enlarged front edge 13, serves to clamp the several operating rings, excepting the rotor, against the shoulder 14 of the housing.

For a more perfect and smooth operation, there are also a central guiding-ring 15 and outer deflecting-rings 16.

Nozzle-jets 17 are made as mere impressions in the face 18 of the jet-rings 10. Any fog-nozzle is provided with at least one pair of these rings, the pair being placed face to face in operative position.

The pair of jet-rings is preferably always keyed in proper position on the main housing 8, as indicated at 21 in Fig. 1, to always retain its properly aligned position with respect to the openings 9 in the housing.

In order to be actuated by the nozzle-discharges, the inner faces of the rotor are provided with pockets or notches 22, indicated in Figs. 1 and 10.

Any escape, by way of the openings 9 in the housing, to result in a discharge from the jets 17, to act upon the rotor by means of the pockets 22, is made to pass through the passages 23 in the deflecting rings 16 outwardly beyond the rotor.

In this action of being flung, or centrifugally thrown outwardly, the discharge is deflected upon, or along the front face 24 of the rotor by the outermost edges 27 of the deflecting-rings 16, to be finally impinged from opposite sides over the outermost front edge 25 of the rotor.

A vaporizing is thus accomplished by repeated breaking up of the passing matter in its path through the housing and rotor; first being divided through the several openings 9; secondly being forced through the narrow, flattened jet-ends 17; thirdly being forced against the pockets 22 of the rotor; fourthly being deflected through the passages 23; fifthly being deflected by the ring-edges 27; and, finally, being impinged over the front edge 25.

The passing of matter from the opening 9 to

the jet-ends 17 should be clear from the illustration in Fig. 1, where it is indicated that the jet-end 17a is flattened and broadened to a width, to easily pass the ring 15. This feature is, moreover, made clearer by the illustrations in Figs. 2 to 8; particularly, Figs. 3, 5, 7 and 8, where the widening space of the nozzle-jet 17a is amply clearing the ring 15.

The simple device, illustrated in Fig. 1, may be said to deliver a definite amount of discharge in a certain manner, when once assembled; which may be changed only by inserting packing materials of different thicknesses in the different joints between the several rings.

On the other hand, the arrangement of Fig. 9 allows many adjustments with the same assembly, to be handled by any unskilled person under directions of the manufacturer, and to be realized from easily readable indicators on the device.

Of course, all sorts of make-shifts can be made for getting variations in the resulting spraying. Jets in lower or upper ring-halves can be made of slightly different sizes so as to get a stronger spray in one or another direction. Ring-halves can be packed so as to produce more or less discharge to one or the other of the rotor-halves, so as to get or have a larger or smaller discharge from one side or the other over the front or outer faces of the rotor, to, thereby, cause the impingement over the front-edge 25 to be stronger one way or the other, upwardly, or downwardly. All such makeshifts, however, are only troublesome.

Nevertheless, it can be of great advantage, when it is required or desired to have a fog discharged in certain directions or to have it hang or remain in certain places predominantly; to have for such various purposes certain and definitely operating means by which to get such results at will.

Extra, definitely operating adjusting means are therefore provided in the modification illustrated in Fig. 9. Adjustments for such predominance are provided at the very exit of the discharge; the adjusting-rings 28 having over-reaching edges 29 for controlling the passages 23, and these over-reaching edges may, of course, extend closer to the very front edge 25, 29a indicating such condition in Fig. 14. The impingement may thus be controlled more closely to the very final discharge from the nozzle. Predominantly forceful discharge may thus also be diverted upwardly or downwardly to suit requirements. The lock-rings 30 serve to maintain the rings 28 in adjusted position. Pointers 31 are provided on the lock-nuts or rings 30, to indicate predetermined positions by means of graduations, easily provided on the front edge at 32, though not particularly illustrated in the drawing since that sort of thing is well enough known to not necessitate further showings.

These rings 28 and 30, thus mounted adjustably on the extensions of the modified deflecting-rings 16a, may be set in predetermined positions for definite larger or smaller discharges on one side or the other of the rotor, or in positively equal forces, to assure any desired results.

The outermost edge 25 may be a part of the rotor, as described herebefore, or it may be a part of the ring 15, the ring 15a being thus modified, to extend through the rotor. Fig. 12 illustrates another slightly modified form in ring 15b, in which a pin 20 connects the two rotor-halves 11b with the ring for uniform rotation,

Fig. 13 illustrates still another slightly modified form 15, which is provided with a diverting portion 26, to overlap the innermost edges of the rotor-halves, for diverting the passing stream in such a manner as to not force itself too strongly between the rotor-halves and the ring 15b.

Though illustrated variously, this ring 15 is really adapted merely for the different purposes for which the whole nozzle is useful; in the form of a guiding- or bracing-ring, to maintain the rotor-halves, as much as possible and practical, centrally and against sidewise movements; deflecting and diverting, by embodying the front edge 25 which is otherwise a part of the rotor-halves, and embodying the portions 26, to prevent undesired leakage between the several rings, thereby bringing the pressure to the opposite side of the rotor to the utmost; and connecting the rotor-halves for joint operation as in Fig. 12.

From the foregoing, it will be understood that the rotor-halves can be made to operate in distinctly different circulating or rotating directions by the mere application of suitably co-operating nozzle-halves.

Having stipulated in the foregoing preamble a making of the nozzle-rings by the die-casting process, it serves to facilitate the most accurate shaping of even difficult nozzle-orifices or passages at the least cost for their manufacture, and the safest and surest application of the proper, or even any, nozzle-rings by even any unskilled person for the most efficient and practical use.

It is definitely possible to make, either the application of the nozzle-halves in the manner illustrated in Fig. 2, or the extremely opposite application of the nozzle-halves in the manner illustrated in Fig. 6, most effective and efficient under different conditions and for different purposes, though under and with very similar construction for and of the whole or complete fog-nozzle.

From this, it then follows that, if both rings of a pair are provided with jet-impressions of the same design, both jets, either, in the form of Fig. 10, or in the form of Fig. 11, the jet-outlets pointing in one and the same direction when looking at the upturned faces of such rings, the effect of the pair is that the combined jet-outlets, or orifices, will point in opposite directions when such a pair is placed face upon face as illustrated in Figs. 2, 3, 4, and 5; while, on the other hand, if one of the rings of the pair is provided with impressions as illustrated in Fig. 10, and the other ring of the same pair is provided with impressions such as illustrated in Fig. 11, this arrangement will result in a combined nozzle and jet system in which oppositely placed rings, face to face, will form co-operating joint-jets, with each pair of jets in both rings of the pair pointing in the same direction, as illustrated in Figs. 6, 7 and 8.

This idea is made use of for different purposes. For instance, it may be the principal object, and therefore desired and required in a certain project, to provide for the greatest amount of discharge, regardless of anything else; in which case the joint operation of both jet-rings of the pair in the same direction may satisfy best, inasmuch as they operate against the least resistance, and, simply forcing both the rotor-halves to the greatest speed possible, to result in the greatest centrifugal force, by which to discharge the greatest volume possible, though the impingement may not be very strong, since the discharges from opposite sides of the rotor

will be at such an acute angle as to be rather parallel tangentially to the rotor, due to the joint, and joined, equally rotating centrifugally discharging action.

For another purpose, on the other hand, the impressions may be made to appear alike when looking at the upturned faces in the pair of jet-rings, which would cause the rings, when turned and placed face to face, to discharge in opposite directions, which, in turn, will create and cause forces to act differently on oppositely disposed rotor-halves, whereby the discharge from one side of the rotor will be impinged against the discharge from the opposite side of the rotor, not only by reason of the angular meeting over the outer faces of the combined rotor-halves but, additionally, by reason of the oppositely rotating centrifugal discharges from the oppositely actuated rotor-halves, really acting tangentially against one another, thereby resulting in a more forceful impingement over the front faces of such rotor-halves, though it may lower the speed of the rotor-halves and therewith lower the amount of discharge, compensated for only by applying greater operating force.

That the discharge from any jet is not materially impaired by the somewhat surrounding arrangement of the central ring 15, as might erroneously be believed from the illustration of Fig. 1, is made clearer by the illustrations in Figs. 3, 5, 7 and 8. Particularly Figs. 5 and 8 show quite definitely that the broadening and flattening of the jet is sufficiently spread before it reaches the ring 15 at the points A and B, see also, and compare with, Figs. 2 and 6, so that the discharge may easily reach the orifice 17a, which is also indicated in Fig. 1. The section-lines R—R and L—L in Fig. 6 give a more definite line of section on which Fig. 1 is taken; L merely designating the left side of Fig. 1, while R designates the right side of Fig. 1. The portions 26 of the modified form of ring 15c in Fig. 13 are made at an angle practically predicated by the slant of the jet as illustrated in Figs. 5 and 8, so that such portion also does not impair the passage to any degree materially, but the shoulders so gained can close any eventually existing gap between the rings, thereby serving to guide the passing liquid so much more over the outside faces of the rotor.

Holding and guiding the rotor in a central position not only provides the best operating conditions for the rotor itself, but, moreover, maintains the equal spacing over both sides of the rotor, as at 23; and a free and most speedy rotation of the rotor helps to keep the passages clear to the extent that such operation practically frees itself of clogging particles.

The large, bowl-like, housing 8 serves as a pressure equalizing tank, eliminating air-pockets that are frequently encountered in supply lines, and this housing, also, provides a space for the insertion of a filter ahead of the nozzles without choking the flow through the device towards the nozzles or jets. In fact, the whole bowl may easily contain a filtering medium with suitable screens, to assure proper operation of the whole fog nozzle.

I claim:

1. The combination, in a fog nozzle of the class described with a general longitudinal axis; of a central control structure having axial intake connection and lateral outlet-openings, an impingement-structure including a rotor and end-rings on opposite sides of the rotor, the rotor

being mounted about said axis and about said lateral outlet-openings and having oppositely inclined faces terminating in an outwardly extending front-edge, the end-rings having portions over-reaching the front of the rotor to points near said edge to deflect passing matter from opposite sides of the rotor so as to impinge over the front face of the rotor laterally in all directions with respect to the central axis of the central structure and fog nozzle.

2. In a fog nozzle of the class described, a central structure having axial intake connection and outlet-openings in a lateral plane, an impingement structure including a rotor and end-rings on opposite sides of the rotor, the rotor being mounted about said outlet-openings and about the axis of said central structure and having oppositely inclined faces terminating in an outwardly extending front-edge, and discharge controlling-rings mounted adjustably on said end-rings and having portions over-reaching said faces of the rotor to points near said edge for varying the discharge over opposite sides of the rotor in the direction of said axis with different results in said plane, portions over-reaching the front to deflect matter passing from opposite sides of the rotor so as to impinge over the front face of the rotor laterally in all directions with respect to the central axis of the central structure and fog nozzle.

3. In a fog nozzle, a central structure with a longitudinal axis having intake connection and outlet-openings, an impingement structure including a rotor and end-rings on opposite sides of the rotor, the rotor being mounted for rotation in a lateral plane transversely to said axis about said outlet-openings and having oppositely inclined faces terminating in an outwardly extending front-edge, and discharge controlling rings mounted adjustably on said end-rings and having portions over-reaching the faces to points near the edge of the rotor whereby oppositely arranged discharges may be adjusted separately one without the other, to deflect matter passing from opposite sides of the rotor so as to impinge over said front-edge in said plane in all directions.

4. In a fog nozzle, a central structure with longitudinal axis having intake connection and outlet-openings, an impingement structure including a rotor and end-rings on opposite sides of the rotor and also including actuating controlling means with jets of variable sizes and forms between said openings and the rotor, the rotor having actuating means and being mounted about said jets of said controlling means to be rotated by passing matter from the openings by way of said jets in thereby predetermined directions due to said forms of said jets and being also provided with an outwardly protruding front-edge, the end-rings having portions over-reaching said rotor to points near said edge, to deflect matter passing from opposite sides of the rotor so as to impinge over the front edge of the rotor in an evenly divided discharge laterally in all directions with respect to the central axis.

5. In a fog nozzle, a central structure with a longitudinal axis having intake connection and outlet-openings, an impingement structure in-

cluding paired actuating controlling rings with jets in the adjoining faces besides paired rotor-halves with actuating means facing said jets and furthermore end-rings on opposite sides of the rotor-halves with portions over-reaching the rotor, there being also a guide and separating ring between the paired jet-rings and rotor-halves for deflecting passing matter from the individual jet-rings to the individual rotor-halves, whereby varied directions of rotations may be predetermined in the opposite rotor-halves, the combined rotor-halves having a protruding front-edge, said end-rings including portions by said over-reaching to extend to points near said front edge, to deflect matter passing from opposite sides of the rotor so as to impinge over the front face of the rotor laterally in all directions with respect to the central axis.

6. In a fog nozzle, a central structure with longitudinal axis having an axial intake connection and lateral outlet-openings, and an impingement structure including a rotor mounted about said openings and having end-rings with portions over-reaching the front of the rotor to deflect matter passing from opposite sides of the rotor so as to impinge over the front face of the rotor in an evenly divided discharge laterally in all directions with respect to the central axis of the central structure and of the whole fog nozzle, the impingement structure embodying a pair of jet-rings with jet-recesses in oppositely arranged faces of the jet-rings by which discharges may be forced in desired circular directions in each of the rings of the pair.

7. In a fog nozzle, a central structure with a general longitudinal axis, the structure having an intake connection and lateral outlet-openings, an impingement structure embodying paired jet-rings each with an inclined face, the combined two faces of a pair forming a hollowed V-shaped center in a plane transversely about said axis, and paired oppositely disposed rotor-halves having each an inclined inner face to jointly fit in said V-shaped center, the rotor-halves having actuating means on said inner faces, the actuating means of the rotor being in front of the escape-ends of the jets in positions to be acted upon by any matter passing through and discharging from said jet-rings to thereby rotate the rotor in the direction corresponding to the direction in which the jets of the jet-rings point.
